United States Patent Office.

DEXTER HEAD, OF MEDUSA, NEW YORK.

Letters Patent No. 79,071, dated June 23, 1868.

IMPROVED HOISTING-APPARATUS.

The Schedule referred to in these Letters Patent and making part of the same.

TO ALL WHOM IT MAY CONCERN:

Be it known that I, DEXTER HEAD, of Medusa, in the county of Albany, and State of New York, have invented a new and improved Hoisting-Apparatus; and I do hereby declare that the following is a full, clear, and exact description thereof, which will enable others skilled in the art to make and use the same, reference being had to the accompanying drawings, forming a part of this specification, in which—

Figure 1 represents a side elevation, partly in section, of my improved hoisting-apparatus.

Figure 2 is a detail transverse section of the same taken on the plane of the line $x x$, fig. 1.

Similar letters of reference indicate corresponding parts.

This invention relates to a new device for elevating loads of suitable description, and consists in the application of a system of levers, known under the denomination of lazy-tongs. By the use of this invention, articles can be elevated to considerable heights with the aid of but inconsiderable motive-power.

A, in the drawing, represents a crane or derrick, of suitable construction and of suitable size. From it is suspended a frame, B, to which the upper levers, $a a'$, of the lazy-tongs C are, by means of a pin, b, pivoted.

The lazy-tongs consist of two sets of zigzag levers, pivoted together in the middle of their bars, as shown. One of these central pivots, e, or a continuation of it, projecting through the slotted upright or uprights of the frame B, does or may serve as handle for the manipulation of the apparatus.

By moving this pin from the lower to the upper end of the slot, the whole system will be contracted, as in fig. 1, as all levers will remain parallel to those elevated with the pin, and as the pin e is brought nearer to the pin b, the levers are brought the nearer to a horizontal position the nearer e is to b.

The opposite motion of the pin e causes the levers to expand, as shown by red lines in fig. 1, and thus, by raising the pin or handle e, the load suspended from the device will be elevated, while it will be lowered when e is moved down.

The distance through which the load is moved is as many times greater than the space in which e moves as there are jointed pairs of levers employed in the system C; consequently, the more such levers are connected, the larger will be the motion of the load in comparison with that of the handle e.

The handle e may be raised by suitable mechanism, either by means of a rope or cord, e, which is wound around a windlass, f, or by other suitable apparatus.

What I claim as new, and desire to secure by Letters Patent, is—

The lazy-tongs C, arranged to operate in connection with the derrick A, slotted frame B, the pulleys, cord e, and windlass f, as herein described, for the purpose specified.

The above specification of my invention signed by me, this 7th day of April, 1868.

DEXTER HEAD.
